GARMENT HANGER

Charles H. Kraft, Kansas City, Mo.

Application September 11, 1950, Serial No. 184,241

2 Claims. (Cl. 211—117)

1

This invention relates to improvements in garment hangers and has particular reference to an adjustable garment hanger operable whereby the garment may be supported at different vertical levels.

The principal object of this invention is the provision of a spring actuated garment hanger adapted to be arranged in spaced apart parallel relation to support garments in parallel relation in their raised position.

Another object of the present invention is the provision of a garment hanger having spring actuating means whereby the garment hangers may be selectively moved to and from the hanging position.

Other objects are simplicity and economy of construction, ease and efficiency of operation, and adaptability for supporting the various types and sizes of garments.

With these objects in view as well as other objects which will appear during the course of the specification, reference will be had to the drawings wherein:

Fig. 1 is a front elevational view of a series of garment hangers mounted in a cabinet.

Fig. 2 is a cross sectional view taken on section line II—II of Fig. 1.

Fig. 3 is an enlarged elevational view of one of the garment hangers with the hanger shown in the raised position.

Fig. 4 is a sectional view taken on line IV—IV of Fig. 3.

Fig. 5 is an enlarged sectional view taken on line line V—V of Fig. 2.

Throughout the several views like reference characters refer to similar parts and the numeral 10 designates a clothes cabinet having a shelf 12 and suitable closure members 14.

The garment hangers 16 are rigidly secured to the under side of the forward edge of the shelf 12 by means of screws 18. This garment hanger comprises an inverted U-shaped frame 20 having depending legs 22 and 24. These legs are spaced apart a sufficient distance to receive the sheave wheel 26 therebetween, which is mounted for rotation on a transverse pin 28 mounted in legs 22 and 24. Pin 28 has a head 27 and is provided at its other end with a cotter key 29 by means of which it is secured against longitudinal movement.

One side of sheave wheel 26 is open as at 30, and is adapted to receive a helical spring 32 therein. One end portion 34 of spring 32 is anchored in the side wall 36 of sheave wheel 26, and the other end portion 38 of spring 32 ex-

5 tends through the open side 30 of the sheave wheel and is anchored in the leg 22 of member 20. This leg 22 is of sufficient size to completely cover the open side of sheave 26.

10 A garment hanger of any of the various types indicated as 40 is supported by a flexible member such as chain 42 which is wrapped around sheave wheel 26 and secured thereto by means of any suitable means. The direction of winding of spring 32 and of the flexible members is such that

when the garment hanger is drawn away from the sheave wheel spring 32 will be wound, thus energizing it sufficiently to drive the sheave wheel in the reverse direction to rewind the flexible member.

15 Integral with or secured to leg 22 is an inclined table 46 having a depending leg 48 which serves as a guide to maintain the hanger in desired general direction as the hanger head 50 is positioned between legs 22 and 48 as shown in

20 Figs. 3 and 4. An opening 52 is formed through table 46 to receive chain 42 therethrough. Table 46 is notched downwardly from opening 52 at 54 to present a recess to receive the reduced portion

25 56 of chain 42, whereby the enlarged portion 58 of the chain will engage the table to prevent longitudinal movement thereof, thereby making it possible to support garments heavier than spring 32 would normally carry. A transverse notch 60 formed in table 46 outwardly from the end of opening 52 is so positioned that when the

30 operator pulls the garment and hanger outwardly to unwind the chain from pulley 26 he may easily force the portion 56 of the chain into the notch to secure the chain against longitudinal movement.

35 When it is desired to again return the hanger to the raised position, this chain is moved from notch 60 and the spring rewinds it on the sheave to move the hanger into the raised position.

40 Referring to Figs. 1 and 2 it will be noted that the garment hangers 40 are held in substantially parallel relation transversely of shelf 12 and can be pulled out to a convenient position for placing the coat thereon or for removing the coat. When so positioned the garments require a minimum amount of space, thus providing a maximum capacity for a given size closet.

45 It will also be noted that when the garment is to be placed on or removed from the hanger the hanger is moved from its normal garment hanging position, thus making the operations easy any convenient at a position removed from the other garments whereby they will not interfere with or disarrange each other.

50 A further advantage of this garment hanger is

that all parts are interconnected so that parts cannot be displaced or lost, especially when they are used in schools by small children.

What I claim as new is:

1. A garment hanger comprising a frame, a sheave rotatably mounted in said frame, a spring member mounted to constantly urge said sheave to rotate in one direction, a flexible member secured to and wound about said sheave, and carrying a coat hanger at its free end, an inclined 10 table carried by said frame and having an opening formed therein to receive said flexible member therethrough, notches formed in said table from the edges of said opening to receive and secure said flexible member against longitudinal 15 movement, and depending members carried by said frame to engage and limit rotation of said coat hanger about said flexible member.

2. A garment hanger assembly comprising a plurality of reels carried rotatably by a support 20 in closely spaced coaxial relation, a flexible member wound on each of said reels, a substantially planar garment hanger attached to the free end of each of said flexible members, spring means urging each of said reels rotatably whereby the 25

associated flexible member is wound on said reel to raise said hanger, and a pair of guide members carried by said support adjacent each of said flexible members and extending downwardly from said support sufficiently to overlap opposite sides of the associated hanger when said hanger is in its raised position, whereby rotation of said hanger about said flexible member is limited.

CHARLES H. KRAFT.
